UNITED STATES PATENT OFFICE.

HELG WIGGO JESPERSEN, OF WESTERN SPRINGS, ILLINOIS, ASSIGNOR TO WESTERN ELECTRIC COMPANY, INCORPORATED, OF NEW YORK, N. Y., A CORPORATION OF NEW YORK.

MECHANISM FOR WORKING FIBROUS MATERIAL.

Application filed October 15, 1926. Serial No. 141,700.

This invention relates to improvements in mechanism for working fibrous material, and more particularly to mechanism for forming pulpos material to constitute a homogeneous coating for cores in strand form, such as wire and the like.

The primary object of the invention is to provide an improved mechanism for rapidly and efficiently forming fibrous material on a core to constitute a homogeneous and uninterrupted coating therefor conforming to the shape of the core.

In accordance with the general features of the invention, there is provided in one embodiment thereof a rotatable member having an axial opening adapted to accommodate a core with a ribbon of pulp attached thereto. A plurality of freely rotating rolls carried by the member are provided with annular flanges which overlap each other so that the peripheral surfaces thereof are in rolling engagement with the attached pulpos ribbon, thereby forming it around the core to constitute a homogeneous coating therefor conforming to the shape of the core. One of the rolls is resiliently supported whereby it is movable under tension away from the other rolls.

Other features and advantages of the invention will become apparent in the following detail description, reference being had to the accompanying drawing, wherein—

Fig. 1 is a longitudinal section, partly in elevation, of a forming mechanism embodying the features of the invention, one of the rolls being omitted for the sake of simplicity;

Fig. 2 is an end elevation thereof;

Fig. 3 is a vertical section taken on line 3—3 of Fig. 1;

Fig. 4 is a fragmentary detail view of a portion of the mechanism shown in Fig. 1;

Figs. 5 and 6 are enlarged sectional views illustrating the manner in which the pulp is applied to the core before it is delivered to the forming mechanism, and

Figs. 7 and 8 are enlarged sectional views showing the formation of the pulp coating immediately after starting the forming operation and after the completion of the forming operation, respectively.

The forming mechanism herein shown and described is adapted to be used in conjunction with the apparatus for coating cores with pulp shown and described in patent to

H. G. Walker, No. 1,615,423, issued January 25, 1927. In the operation of this apparatus a core is brought into contact with pulpos material deposited upon a foraminous member and then an additional amount of pulpos material is deposited upon the core and the foraminous member. The pulp so deposited and the core are then brought into contact with a felt covered squeezing roll which cooperates with the foraminous member to squeeze out the "free liquid" from the pulp. The partially dried pulp adheres to the core in the form of a ribbon with the core substantially centrally located therein, as is shown in Fig. 5 of the accompanying drawing. The core with the pulp ribbon attached thereto is then passed through a plurality of squeezing rolls which impart to the pulpos ribbon a contour such as is illustrated in Fig. 6.

A forming mechanism embodying the features of the present invention is designed to receive a core and its pulpos ribbon from the squeezing rolls and wrap the projecting edges of the ribbon around the core and around each other to form a coating for the core which substantially conforms to the shape thereof. The appearance of the coating immediately after starting the forming operation is shown in Fig. 7 and its appearance after the forming operation is completed is shown in Fig. 8.

Referring now to the drawing in detail, the numeral 10 indicates a supporting head or carrier having a threaded portion 11 by means of which it is secured to a sleeve 12 rotatably journaled in a plurality of bearings, one of which is shown at 13. The sleeve 12 may be rotated by any suitable means (not shown) and thus constitutes means for rotating the carrier 10. The carrier 10 and sleeve 12 are provided with aligned central longitudinal apertures 14 and 15, respectively, for accommodating a core 17 with its attached pulpos coating 18 drawn axially therethrough by any suitable means (not shown).

Secured to the carrier 10 and disposed eccentrically with respect to the rotating axis thereof are a pair of forwardly projecting spindles 20 and 21 (Figs. 1 and 3) upon which are rotatably supported a pair of cylindrical rolls 22 and 23, respectively. In the present embodiment of the invention, the rotating axes of the rolls 22 and 23 are parallel to the rotating axis of the head 10, but it is to be

understood that the invention should not be limited to this particular construction. A roll 24 which may be similar in construction to the rolls 22 and 23 is rotatably carried 5 upon a forwardly projecting spindle 26, which latter spindle is secured to a pivoted member 27 mounted within a recess 28 formed in the carrier 10. The member 27 is pivoted intermediate its ends upon a horizontally disposed pin 30 projecting from the recessed portion of the carrier 10. One end of the member 27 is formed so as to provide a suitable bearing for supporting the spindle 26 which carries the roll 24. A compression spring 10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430

Each of the rolls 22, 23 and 24 is provided with a plurality of spaced annular flanges 35 which are designed to overlap each other as best shown in Fig. 2. The arrangement is such that as the core with its attached ribbon 30 of pulp is drawn axially through the rotating carrier 10 in the direction indicated by the arrow (Fig. 1), the peripheral surfaces of the flanges 35 are constantly in rolling engagement with the pulpos ribbon thereby forming it around the core and around itself so as to constitute an uninterrupted homogeneous coating for the core conforming to the shape thereof as shown in Fig. 8. The annular flanges formed upon the forward ends of the rolls are of smaller diameter and tapered as indicated at 36. Due to this construction, the pulpos ribbon is gradually formed around the core as the core is drawn through the forming mechanism, thus preventing any stripping of the pulp from portions of the core. The formation of the pulpos ribbon after it is first acted upon by the smaller flanges 35 is illustrated in Fig. 7.

In the operation of the above described 50 forming mechanism, the core 17 with its attached ribbon of pulp 18 is drawn axially through the carrier 10 and sleeve 12 in the direction indicated by the arrow (Fig. 1), the carrier and sleeve being rotated by any 55 suitable means (not shown), thus causing the rolls 22, 23 and 24 to be rotated bodily around the moving core. In so doing the rolls also rotate on their own axes due to the frictional contact between the pulpos ribbon and the peripheral surfaces of the flanges 35, thus causing the pulpos ribbon to be rolled on the core in the same manner as though the core and the pulpos ribbon were rolled on a table top with the palm of the hand. This rolling action of the forming

rolls reduces friction between the pulp and the forming surfaces, thus insuring against stripping of the pulp from portions of the core.

As hereinbefore described, the roll 24 is mounted so as to be movable under tension into a plurality of parallel positions. This construction permits the free passage of any irregularity such as a knot or abnormal thickness of the pulpos material, thus eliminating any danger of the core breaking due to such causes. Furthermore, due to the action of the spring 32, the roll 24 is returned to its normal position immediately after the passage of any such irregularity, thus producing a coating which is of substantially uniform thickness throughout the length of the core. It will be understood, also, that by adjusting the stop 33, the space between the pulp engaging flanges of the rolls 22 and 23 and the pulp engaging flanges of the roll 24 may be changed to accommodate cores of various diameters or to vary the thickness or density of the pulp coating.

What is claimed is:

1. In a mechanism for working pulpos material on a core, a forming member comprising an element movable under pressure into a plurality of positions wherein it engages the pulpos material and having a cylindrical surface constantly in rolling engagement with said pulpos material. 90
2. In a mechanism for working fibrous material on a core, a forming member comprising a resiliently mounted element having a cylindrical surface constantly in rolling engagement with said fibrous material. 100
3. In a mechanism for working fibrous material on a core, a forming member comprising a rotatable element movable under pressure into a plurality of parallel positions wherein it engages the fibrous material and having a cylindrical surface constantly in rolling engagement with said fibrous material. 105
4. In a mechanism for working fibrous material on a core, a plurality of rotatable forming members having cylindrical surfaces constantly in rolling engagement with the fibrous material, one of said forming members being movable under pressure into a plurality of positions in accordance with variations in the amount of fibrous material on the core. 110
5. In a mechanism for working pulpos material on a core, a plurality of forming rolls adapted to be rotated around the core, each of said forming rolls having an annular flange designed to overlap the flange of another roll to cause the peripheral surfaces thereof to constantly engage the pulpos material. 120
6. In a mechanism for working fibrous material on a core, a plurality of forming rolls having overlapping annular flanges constant-

ly in rolling engagement with the fibrous material.

7. In a mechanism for working pulpos material on a core, a plurality of forming 5 rolls having overlapping annular flanges constantly in rolling engagement with the pulpos material, one of said rolls being movable under spring tension into a plurality of parallel position in accordance with variations in 10 the amount of pulpos material on the core.

8. In a mechanism for working pulpos material on a core, a plurality of forming rolls having overlapping annular flanges constantly in rolling engagement with the pulpos 15 material, one of said rolls being movable under spring tension into a plurality of parallel positions in accordance with variations in the amount of pulpos material on the core, and means for limiting said movement in a 20 given direction.

9. In a mechanism for working pulpos material on a core, a rotatable carrier, a plurality of forming rolls eccentrically support-

ed with respect to the axis of said carrier, each of said forming rolls having an annular 25 flange overlapping an annular flange of the other rolls, and means for rotating said carrier whereby the peripheral surfaces of said annular flanges are constantly in rolling engagement with the pulpos material. 30

10. In a mechanism for working fibrous material on a core, a forming member comprising a freely rotatable element having spaced projections continually engaging the 35 pulpos material.

11. In a mechanism for working pulpos material on a core, a forming member comprising a freely rotatable element having spaced projecting portions of progressively increasing diameter continually engaging the 40 pulpos material.

In witness whereof, I hereunto subscribe my name this 30 day of September, A. D. 1926.

HELGO WIGGO JESPERSEN.
